SERVING TRAY

John L. Mohun, Chicago, Ill.

Application September 9, 1946, Serial No. 695,649

5 Claims. (Cl. 65—5)

1

My invention, which pertains to serving trays, has among its important objects the provision of a combination serving tray which includes an ash receiver and glass support with improved means for detachably interlocking the component parts, snuffing cigars and cigarettes, and which may be economically manufactured.

Broadly speaking I attain these and other objects by securing a cylindrical retainer in the center of a dished tray. A perforated ring-shaped glass or bottle rest is fitted around the retainer and into the tray, being spaced upwardly from the bottom of the tray by spring clips. An ash receiver disposed within the retainer is urged upwardly by a resilient arch formed in the base of the tray and so acts against a cover-plate held to the retainer by a bayonet lock and studs to lock the cover removably to the retainer. Since the cover-plate also extends downwardly around the retainer and into contact with the upper surface of the glass rest, it may be seen that the glass rest is also resiliently locked in place but at the same time may be conveniently removed for cleaning.

Because of the resilient nature of the interlocking relationship between the parts, the possibility of accidental removal or excessive movement between the members is eliminated as is the necessity for forming the parts to relatively close tolerances. The cover-plate may be provided with my novel match holder, or a pipe reamer, and with a series of openings each converging to a point, the edges of such openings being relatively sharp to assist in clipping the ignited end of a cigar or cigarette butt.

For a more detailed description, reference is made to the following specification and drawings in which

Figure 1 is a top view of my device;

Figure 2 is a side view;

Figure 3 is a vertical cross section;

Figure 4 is a partially sectioned side view of a portion of my device;

Figure 5 is a perspective view of my novel match holder; and

Figure 6 is a perspective view of a spring clip.

As best seen in Figures 1 and 3, a tray 10 may be drawn from sheet metal, forming a relatively flat bottom 11 having a centrally disposed upwardly extending resilient arch 12. The outer portion of the bottom 11 curves upwardly and outwardly as at 13 to a vertical side wall 14 having a beaded edge 16. The tray may be attached to a suitable stand or may be provided with spaced pads 15 for table use. A cylindrical re-

2

tainer 17 is secured to the bottom 11 around the arch 12 by angle clips 18 riveted to the retainer 17 and the bottom 11, and may in addition be welded or otherwise sealed to form a watertight joint.

Legs 19 of the clips 18 extend outwardly from the retainer 17 to resiliently support the inner edge of a glass rest 21. The glass rest 21 is a disk of stainless steel, Bakelite, or other suitable noncorrosive incombustible material having a central aperture slightly larger than the diameter of the support 17. The outer edge of the glass rest 21 rests on the curved portion 13 of the tray 10 and is slotted as at 22 to clear inwardly extending lugs 23 attached to the side walls 14. Drain holes 24 extend through the rest 21. For convenient removal, finger holes 26 are also provided in the rest 21 to facilitate rotation and alignment of the slots 22 with lugs 23. A cup-shaped receiver 27 of metal, glass, plastic, or other suitable material, is formed to fit within the retainer 17 in contact with the arch 12 which normally resiliently supports the upper edge of the receiver 27 a short distance above the upper edge of the retainer 17. Inwardly extending lugs 25 may be secured to the inner surface of the receiver 27 to assist in removal. A cover-plate, generally designated 28, is telescoped over the retainer 17 and the receiver 27 and is provided with an outwardly extending edge flange 29 disposed to engage the upper surface of the glass rest 21. Headed studs 31 extend outwardly from the retainer 17 to engage T-shaped slots 32 having a vertical section 33 and a horizontal section 34 formed in the cover-plate 28 adjacent the flange 29. When first applied, the inner surface of the cover-plate 28 rests on the upper edge of the receiver 27, and as the cover-plate 28 is pressed downwardly by the hand, the receiver 27 flexes the resilient arch 12 and the studs 31 pass through the vertical section 33 of the slots 32. Rotation of the cover-plate 28 then engages the horizontal section 34 of the slots 32 with the studs 31 locking the cover-plate in place, the flange 29 in this process engages the upper surface of the glass rest 21, forcing it downwardly against the resilient legs 19 of the clips 18 thus locking the glass rest 21 in position.

A central portion 36 of the cover-plate 28 within the receiver 27 is dished downwardly and provided with a plurality of openings 37 disposed radially about a center portion 38 and communicating with receiver 27. The openings 37 may suitably be curved at their outer ends with substantially straight sides converging to a point 39 near

the center 38 defining a shape which will conveniently receive the bowl of a pipe. The outermost portions of the opening 37 may be provided with downwardly extending flanges 41 but the edges adjacent the points 39 are not flanged and are relatively sharp in order to clip the ignited ends of a cigar or cigarette from the butt. If desired, serrations 42 may be formed around the points 39 to assist in the clipping action.

Semicylindrical cigar rests 43 may be attached to the cover-plate 28 at convenient locations around the central portion 36. Either a pipe reamer 44 or a match holder 46 may be attached to the center 38, according to the desires of the user. The pipe reamer 44, which is tapered, may be formed by welding together two channel members 47 having backs 48 and flaring side walls 49 attached to a suitable base 51. My match holder 46 comprises a channel-shaped member having a web 52 and flanged side walls 53 adapted to receive the striking end of a book of matches. One of the walls 53 is provided with an elongated opening 54 to expose the striking surface of a match base. A base 56 may be attached to the web 52 and threaded to receive a bolt adapted to extend through an opening 57 in the center 38.

From the foregoing description it may be seen that the glass rest 21 provides a convenient support for glasses from which overflow or condensate can drain through the holes 24 into the tray 10, thereby preventing damage to furniture and, in addition, will prevent forgotten burning cigarettes from falling from the rest 43 onto a table or a rug.

Because of the unique locking arrangement of the component parts of my device, accidental removal or separation is prevented even though the tray is dropped, but detachment for cleaning is easily accomplished. Furthermore, because of the resilient nature of the lock, objectionable rattles are eliminated without the necessity of forming the parts to close tolerances or providing padding at appropriate points.

The glass rest will conveniently support glasses, bottles, and other containers, any leakage or condensate falling through the drain holes 24. Ashes or other debris may also be dropped through the holes by running a rag or brush along the rest.

It is not essential that the central portion of my serving tray be used as an ash receptacle. For example, the receiver 27 may be filled with water, and flowers inserted in the openings 37, or a cover-plate open in the center to expose the receiver 27 may be substituted for the cover-plate described, thus making available a convenient container for nuts, candy, or the like.

I recognize that in view of the foregoing description various changes and modifications will occur to those skilled in the art; for example, the resilient arch 12 formed in the tray 10 may be eliminated and the bottom of the receiver 27 arched to provide the requisite resilient action; or springs interposed between the receiver 27 and the bottom 11 of the tray 10 may be substituted. Similarly, other rests and supports can be employed to lock the glass rest 21 in place without departing from the fundamentals of the interlocking system herein described. I therefore do not wish to limit myself to the details herein described except in so far as defined by the appended claims.

I claim:

1. A serving tray comprising a tray having a centrally disposed arch, a cylindrical retaining means extending upwardly from the tray around

the arch, a receiver in the retaining means resting on said arch, a glass rest around the receiver within the tray, a cover-plate extending over the receiver and downwardly into engagement with said rest, resilient means for spacing the rest from the bottom of the tray, and means for removably securing the cover-plate to the retaining means.

2. A serving tray including a tray, a cylindrical retainer attached to the tray, a glass rest within the tray and around the retainer, means for resiliently supporting the glass rest above the bottom of the tray, a receiver in the retainer, resilient means for normally supporting the rim of the receiver slightly above the rim of the retainer, studs fixed to the retainer, and a cover-plate telescoped over the receiver and retainer and engaging the glass rest, the cover-plate having slots disposed to engage the studs for locking the cover-plate in position.

3. A serving tray including a tray, a cylindrical retainer attached to the tray, a glass rest within the tray and around the retainer, means for resiliently supporting the glass rest above the bottom of the tray, a receiver in the retainer, resilient means for normally supporting the rim of the receiver slightly above the rim of the retainer, studs fixed to the retainer, and a cylindrical cover-plate telescoped over the receiver and retainer and engaging the glass rest, the cylindrical cover-plate having slots disposed to lockingly engage the studs only when the telescoped portion of said cover-plate is in compressing engagement with the glass rest and receiver.

4. A serving tray including a tray, a retainer extending upwardly from the tray, resilient means for normally supporting the rim of the receiver slightly above the rim of the retainer, a glass rest within the tray and around the retainer, means for resiliently supporting the glass rest above the bottom of the tray, studs secured to the retainer, and a cover-plate telescoped over the receiver and retainer, the telescoped portion of said cover-plate being sufficiently extensive to compressingly engage said glass rest, and having slots disposed with respect to the end of the cover-plate as to lockingly engage said studs only when the cover-plate is in compressing engagement with said glass rest.

5. A serving tray including a tray having a centrally disposed arch, a cylindrical retainer attached to the tray, a glass rest within the tray and around the retainer, means for resiliently supporting the glass rest above the bottom of the tray, a receiver in the retainer resting on said arch, studs secured to the retainer, and a cylindrical cover-plate telescoped over the receiver and retainer and engaging the glass rest, said cover-plate having slots disposed to lockingly engage with the studs only when the telescoped end of the cover-plate is in compressing engagement with the glass rest and receiver.
